6 Claims. (Cl. 103—37)

This invention relates to variable displacement hydraulic pumps of the reciprocating piston type in which the pistons are mounted in a stationary cylinder block. More particularly, the invention is concerned with the mechanism for varying the displacement of such pumps.

Pumps of this type include a rotary drive shaft carrying a cam which is arranged to coact with the pistons and move them on their discharge strokes in timed sequence, inlet and discharge passages connecting the working chamber of each piston with the inlet and discharge ports, respectively, and valve means for preventing reverse flow from the discharge port to the working chambers through the discharge passages. Each inlet passage is connected with one cylinder bore by a port which is so located as to be overtravelled and closed by the associated piston during the discharge stroke of that piston. Because of this, a portion of the fluid displaced by each piston is returned to the inlet port even during maximum displacement operation. In a typical case, 60° of each revolution of the cam is required to overtravel the inlet port, thus having only 120° of movement for actual pumping operation. Frequently, these pumps employ a by-pass mechanism which diverts a portion of the output of each piston through the pump housing for the purpose of cooling the housing. Approximately 30° of cam rotation is required to produce this bypass flow. As a result, only 90° out of the maximum of 180° of cam rotation is actually used to discharge pressure fluid from the pump. Furthermore, the by-pass flow mentioned above is produced even during conditions of maximum displacement operation. This reduces the efficiency of the pump unnecessarily because the cooling afforded by the by-pass flow is required only during conditions of minimum displacement operation. In those pumps in which the inlet port communicates with the space in the housing surrounding the cam, the pump can be operated with high inlet pressurization only if a positive piston return mechanism is provided. Spring return devices cannot be employed because the fluid pressure forces acting on opposite ends of each piston at the beginning of the suction stroke are not balanced. Springs of a size sufficient to overcome the fluid pressure unbalance would increase the bearing loads on the cam beyond a tolerable limit.

The object of this invention is to provide an improved displacement-varying mechanism for pumps of the type described which results in a pump free from the disadvantages just mentioned. According to the invention, the inlet passage leading to each cylinder bore is provided with an inlet valve which is shiftable between passage-opening and passage-closing positions and which is biased by a spring and by the fluid pressure in the cylinder bore toward the passage-closing position. Each inlet valve is connected with a control motor whose working chamber is in communication with the inlet port and which functions to shift the valve in the opposite direction during the suction stroke of the associated piston. The invention provides a control valve which operates in timed relation with the cam to interrupt com-

2

munication between the working chamber of each control motor and the inlet port when the associated piston reaches a predetermined point in its suction stroke, and to reestablish this communication when that piston reaches a certain position in its discharge stroke. In the preferred embodiment, the certain position and the predetermined position are equidistant from the top dead-center position so that the displacement-varying mechanism operates independently of the direction of rotation of the cam. Connected with the control valve is a regulating device which is effective to vary the said certain position at which communication between each control motor working chamber and the inlet port is reestablished. When the working chamber of a control motor is disconnected from the inlet port, the motor becomes hydraulically locked and the pressure in the associated cylinder bore is ineffective to close the inlet valve. As a result, fluid displaced by each piston during this portion of its discharge stroke returns to the inlet port.

When each piston reaches said certain position, communication between the working chamber of the associated control motor and the inlet port is reestablished and the inlet valve closes under the action of the spring and the fluid pressure in the cylinder bore. For the remaining portion of its discharge stroke, the fluid displaced by each piston is delivered to the discharge port. Since the regulating device governs the time during each discharge stroke that the associated inlet valve is open, it will be apparent that the invention serves to vary the effective displacement of the pump.

The invention also provides by-pass passages, one of which connects each cylinder bore with a by-pass port. Flow through these by-pass passages is controlled by a by-pass valve which is normally closed but which is automatically opened when the control valve is interrupting communication between the working chambers of the control motors and the inlet port for a maximum portion of the discharge stroke of the pump pistons.

A pump embodying this invention is superior to its prior counterparts because it utilizes a 180° discharge stroke during conditions of maximum displacement operation and because it creates a by-pass flow only during minimum displacement operation. Furthermore, since the working chambers of the control motors communicate with the inlet port, spring return devices can be used for the pistons even when the inlet is pressurized a substantial amount. This is attributable to the fact that the pressure in the inlet port is transmitted to the working chambers of the control motors and causes these motors to open the inlet valves and thus equalize the pressures acting on opposite ends of the pistons during their suction strokes.

The preferred embodiment of the invention will now be described in detail with reference to the accompanying drawings, in which:

Fig. 1 is an axial sectional view of a swash plate pump incorporating the invention; the control valve being shown in its maximum displacement-establishing position.

Fig. 2 is an elevation view of the sleeve of the control valve.

Fig. 3 is a sectional view taken on line 3—3 of Fig. 1.

Fig. 4 is an axial sectional view of the control valve showing the relative positions of the two valving elements in an intermediate displacement-establishing position.

Fig. 5 is a sectional view taken on line 5—5 of Fig. 4.

Fig. 6 is a view similar to Fig. 4 but showing the relative positions of the two valving elements in the minimum displacement-establishing position.

Fig. 7 is a sectional view taken on line 7—7 of Fig. 6.

As shown in Figs. 1 and 2, the pump comprises a housing having separable sections 11 and 12 which are

connected together by bolts 13 and which are cored and bored to receive and hold a cylinder block 14. The cylinder block contains a circular series of nine uniformly spaced cylinder bores 15 for receiving the pistons 16. At its left end, each piston 16 carries a shoe 17 which is in sliding engagement with the swash plate 18. The pistons are reciprocated in the bores 15 by the action of swash plate 18 and springs 19.

The housing section 11 contains an inlet port 21 which communicates with the cylinder bores 15 through the chamber 22, formed in section 11, and the longitudinal and radial passages 23 and 24 formed in cylinder block 14. Flow into each cylinder bore is controlled by an inlet valve 25 whose opposite end faces 26 and 27 are subject to the pressure in the cylinder bore and develop pressure forces which, together with spring 28 and the control motor described below, shift the valve in opposite directions during the suction and discharge strokes of the associated piston 16. Fluid under pressure, discharged from each cylinder bore 15, passes through a check valve 29 into the annular discharge manifold 31 and is delivered to the hydraulic circuit by the discharge port 32.

Each inlet valve 25 carries a shoulder 33 which serves as the piston of a control motor 34. The working chamber 35 of each control motor is connected by a passage 36 with a control valve 37 which functions to vary the time during each revolution of swash plate 18 that each working chamber 35 is in communication with inlet port 21. Control valve 37 includes a ported sleeve 38 which reciprocates in an axial bore formed in the cylinder block but which is prevented from rotating by a pin 39, and a rotary valve plunger 41 which is connected in driven relation with swash plate 18 by splined coupling shaft 42. The outer periphery of sleeve 38 contains a series of nine uniformly spaced longitudinal slots 43, each of which communicates with one of the passages 36 and is connected with the interior of the sleeve by a drilled radial passage 44. The rotary plunger 41 is formed with an annular groove 45 which defines two spaced valve lands 46 and 47; the left edge 48 of land 47 lying in a plane which is inclined relatively to the axis of the plunger. Axial and radial passages 49 and 51, formed in plunger 41, connect the groove 45 with the chamber 52 contained in housing section 12. This chamber is in continuous communication with inlet port 21 via passages 53 and 23 and chamber 22. Sleeve 38 is biased to the position shown in Fig. 1 by coil spring 54 and is moved to the right against this bias by a valve motor 55 having a working chamber 56 and a piston 57 which is defined by a shoulder formed on the outer periphery of the sleeve. Working chamber 56 communicates with discharge manifold 31 through passage 58 and a restricted conduit formed in restrictor plug 59.

The cylinder block 14 also contains a plurality of radial passages 61 which connect the cylinder bores 15 with a by-pass valve carried by control valve sleeve 38. The by-pass valve includes a land 62 and a groove 63 formed in sleeve 38; the land 62 normally closing the passages 61. The groove 63 is so dimensioned and located that, when the sleeve 38 is in its minimum displacement-establishing position (see Fig. 6), it connects the passages 61 with the by-pass port 64 through the passage 65. The connection between each passage 61 and cylinder bore 15 is so located that it is overtravelled and sealed by the inlet valve 25 when this valve is open. This arrangement prevents reverse flow from passages 61 to cylinder bores 15 during minimum displacement operation.

Operation

When the pump is running and discharge pressure in manifold 31 is below a predetermined value, termed the "reference value," the force developed by valve motor 55 is insufficient to overcome the bias of spring 54 and control valve sleeve 38 will take up the position shown

in Fig. 1. In this position, edge 48 of land 47 has not overtravelled any of the passages 44 so the working chambers 35 of the control motors 34 will be in continuous communication with inlet port 21 through passages 36, slots 43, drilled passages 44, plunger groove 45, radial and axial passages 51 and 49, chamber 52, passages 53 and 23, and chamber 22. When a piston 16 commences to move to the left on its suction stroke, a pressure is produced in bore 15 that is less than the inlet pressure in working chamber 35 of the associated control motor, and consequently the motor 34 opens the inlet valve against the bias of spring 28 and the net pressure force developed by end faces 26 and 27. This allows the fluid entering inlet port 21 to flow into the cylinder bore 15. As each piston 16 approaches its outermost or bottom dead-center position, the pressure in bore 15 increases, the spring 28 begins to shift the valve 25 to the right toward its closed position. When the piston reaches its bottom dead-center position, the pressures in bore 15 and working chamber 35 will have equalized and the inlet valve 25 will be closed. As the piston 16 starts to move to the right on its discharge stroke, the pressure in bore 15 will rise above that in working chamber 35, with the result that the net pressure force developed by end faces 26 and 27 will exceed the force exerted by control motor 34. The difference between the net pressure force and the force developed by motor 34 will aid spring 28 in holding the inlet valve 25 in its closed position. As a result, all of the fluid displaced by piston 16 during its discharge stroke will pass through check valve 29 and manifold 31 and discharge through port 32.

If discharge pressure should rise above the "reference value" (by reason of a decrease in the demand for hydraulic fluid), valve motor 55 will shift sleeve 38 to the right against the bias of spring 54 to a position in which the forces developed by this spring and motor are balanced and the edge 48 has overtravelled some of the passages 44. Such a position is shown in Fig. 4. An inspection of this figure and Fig. 5 will show that during one-half of each revolution of swash plate 18 (i.e., during one-half of one complete pumping cycle of each piston 16), land 47 of rotary plunger 41 interrupts communication between each passage 36 and inlet port 21. Because of the fact that the angular position of each slot 43, about the axis of the cylinder barrel, is the same as that of the cylinder bore 15 with which it is associated, and because of the phase relationship between edge 48 and swash plate 18, this interruption occurs at the mid-point of the suction stroke of each piston 16 and continues until the piston reaches the mid-point of its discharge stroke. Consequently, when each piston 16 begins to move on its suction stroke, the working chamber 35 of the associated control motor 34 will be in communication with the inlet port 21, and the pressure differential between this chamber and the cylinder bore 15 will open the inlet valve 25 and allow fluid to flow into the cylinder bore. When a piston 16 reaches the mid-point of its stroke and the edge 48 of the rotary plunger 41 overlaps the corresponding passage 44, the associated control motor 34 becomes hydraulically locked. This when that piston 16 passes its bottom dead-center position and commences to move on its discharge stroke, spring 28 and the pressure in cylinder bore 15 cannot close the inlet valve 25 and the fluid displaced by the piston will discharge past this valve and into radial passage 24 and longitudinal passage 23. When the piston 16 reaches the mid-point of its discharge stroke and edge 48 uncovers passage 44, the fluid in working chamber 35 can escape and the spring 28 and the net pressure force developed by end faces 26 and 27 will close the inlet valve. The fluid displaced by piston 16 during the remainder of the discharge stroke will pass through discharge check valve 29 to the port 32. It is thus seen that the effective displacement of the pump, when the control valve is in the Fig. 4 position, is one-half of the

displacement established by this valve when it is in the Fig. 1 position.

When the discharge pressure rises to the predetermined maximum, valve motor 55 shifts the sleeve 38 to the minimum displacement-establishing position of Fig. 6 in which the valve land 47 covers each passage 44 for all but a small portion of each revolution of swash plate 18. As the sleeve 38 reaches this position, the annular groove 63 of the by-pass valve overtravels the passages 61 and thus establishes communication between each cylinder bore 15 and the by-pass port 64. As a result, the fluid displaced by each piston 16, during the short time that the associated inlet valve 25 is closed, will be discharged under low pressure through the by-pass port 64. This small by-pass flow serves to cool the pump during the time that the demand for hydraulic oil in the circuit supplied by discharge port 32 is a minimum. Since this flow occurs at a low pressure, little power is required for this purpose.

Although only three positions of the sleeve 38 have been illustrated and described, it will be apparent that control valve 37 effects a progressive variation in displacement as the discharge pressure varies between the "reference value" and the predetermined maximum value. If the spring 54 has a constant rate, the relationship between effective displacement and discharge pressure will be substantially linear.

It will also be apparent that since the distance sleeve 38 moves in travelling between its minimum and maximum displacement-establishing positions is small, spring 54 may have a low rate. This is a desirable feature because it affords a small control pressure differential, i.e., the differential in discharge pressure required to shift sleeve 38 between its limiting displacement-establishing positions is small.

As discharge pressure decreases below the predetermined maximum, the force exerted by valve motor 55 also decreases and spring 54 shifts the sleeve 38 to the left to thereby interrupt the by-pass flow to port 64 and progressively increase the time during each revolution of swash plate 18 that the working chambers of control motors 34 are in communication with the inlet port 21. When the discharge pressure again equals the "reference value," the sleeve 38 will be in its Fig. 1 position and the effective displacement of the pump will be a maximum.

It should be observed that the pressure prevailing at inlet port 21 has no adverse effect on the basic operation of this pump even though springs are used to move the pistons on their suction strokes. This is attributable to the fact that the working chamber of each control motor 34 is always in communication with the inlet port at the beginning of the suction stroke of the associated piston 16, and therefore high inlet pressures actually aid opening of the inlet valves. Once open, these valves remain open for the balance of the suction stroke and therefore, the fluid pressure forces acting on opposite ends of pistons 16 are balanced during the entire suction stroke and the return function of springs 19 is not impaired.

It should also be noted that in the illustrated embodiment, the rotary plunger 41, and particularly the edge 48, is symmetrical about a vertical axis as viewed in Figs. 3, 5 and 7. As a result, during partial displacement conditions (i.e., when sleeve 38 is in a position other than the one shown in Fig. 1), the point in the suction stroke of each piston 16 at which edge 48 overtravels the associated passage 44 is the same distance from the top dead-center position as the point in the discharge stroke at which this passage is reopened. This is a desirable feature because it renders the operation of the displacement-controlling mechanism independent of the direction of rotation of swash plate 18.

As stated previously, the drawings and description relate only to a preferred embodiment of the invention. Since many changes can be made in the structure of this

embodiment without departing from the inventive concept, the following claims should provide the sole measure of the scope of the invention.

What is claimed is:

- 5 1. In a pump including inlet and discharge ports, a stationary cylinder block containing a plurality of cylinder bores, a piston reciprocable in each bore and defining therewith a working chamber whose volume is varied by the motion of the piston, a rotary drive shaft carrying a cam which is arranged to coat with the pistons and move them on their discharge strokes in timed sequence, inlet and discharge passages connecting each working chamber with the inlet and discharge ports, respectively, and valve means for preventing reverse flow from the discharge port to the working chambers through the discharge passages, the improvement which comprises inlet valves, one located in each inlet passage and each being shiftable between passage-opening and passage-closing positions; means responsive to the pressure in each cylinder bore for urging the associated inlet valve toward its passage-closing position; resilient means biasing each inlet valve toward its passage-closing position; control motors, each having a working chamber and a movable element subject to the pressure in that chamber and connected with one inlet valve for moving that valve toward its passage-opening position against the bias of the pressure responsive means and the resilient means; a motor passage connecting each control motor working chamber with the inlet port; valve means operable in timed relation with the cam for closing each motor passage when the associated piston reaches a predetermined position in its suction stroke and for reopening each passage when the associated piston reaches a predetermined position in its discharge stroke; and regulating means connected with the valve means for varying the said certain position at which the passages are reopened to thereby vary the effective displacement of the pump.
- 10 2. The invention defined in claim 1 in which the said predetermined position and the said certain position of each piston are equidistant from the top dead-center position; and in which the regulating means is effective to shift these two positions equal amounts and in the same direction.
- 15 3. In a pump including inlet and discharge ports, a stationary cylinder block containing a plurality of cylinder bores, a piston reciprocable in each bore and defining therewith a working chamber whose volume is varied by the motion of the piston, a rotary drive shaft carrying a cam which is arranged to coat with the pistons and move them on their discharge strokes in timed sequence, inlet and discharge passages connecting each working chamber with the inlet and discharge ports, respectively, and valve means for preventing reverse flow from the discharge port to the working chambers through the discharge passages, the improvement which comprises inlet valves, one located in each inlet passage and each being shiftable between passage-opening and passage-closing positions; means responsive to the pressure in each cylinder bore for urging the associated inlet valve toward its passage-closing position; resilient means biasing each inlet valve toward its passage-closing position; control motors, each having a working chamber and a movable element subject to the pressure in that chamber and connected with one inlet valve for moving that valve toward its passage-opening position; a motor passage connected with each control motor working chamber; a common passage connecting the motor passages with the inlet port; a control valve located at the junction of the motor passages and the common passage and having two coaxial valving elements which are arranged for relative rotational and longitudinal movement, one of the elements being formed with a circular series of ports, here being one port connected with each motor passage, and the other element carrying a control edge which is so shaped that relative longitudinal movement between
- 20

- 65
- 70

the two valving elements in one direction causes a progressively increasing number of ports to be overtravelled by the edge, said other element interrupting communication between a port and the common passage when the edge overtravels that port; means biasing one of the valving elements in the longitudinal direction toward a position in which the control edge overtravels a minimum number of ports; a valve motor for shifting said one valving element in the opposite direction against the biasing means to a position in which the control edge overtravels a maximum number of ports; and means forming a driving connection between the drive shaft and one of the valving elements for producing relative rotation between the ports and the control edge in timed relation with the movement of the pump pistons, the parts being so arranged that said relative rotational movement causes each port to be overtravelled during the suction stroke of its associated piston and reopened during the discharge stroke of that piston.

4. The invention defined in claim 3 which includes 20 a by-pass port; by-pass passages connecting the by-pass port with each of the working chambers of the pump pistons; a by-pass valve normally closing the by-pass passages; and means operatively connecting the by-pass valve and the valve motor, whereby when said one valving element of the control valve is in the position in which the maximum number of ports are overtravelled the by-pass valve is open, and when that control valve element is 25

in the position in which the minimum number of ports are overtravelled the by-pass valve is closed.

5. The invention defined in claim 3 in which the parts are so selected and arranged that the distance each piston travels between the point at which the associated control valve port is overtravelled and the bottom dead-center position is the same as the distance that piston travels between the bottom dead-center position and the point at which that port is reopened.

6. The invention defined in claim 4 in which flow through each by-pass passage is also controlled by one of the inlet valves, the parts being so arranged that each inlet valve opens and closes the associated by-pass and inlet passages in reverse senses.
